SELF-ADJUSTING RECIRCULATING
OVERFLOW

James B. Crawford, Los Angeles, Calif., assignor
to Paddock Pool Maintenance Co., Los Angeles,
Calif., a corporation of California

Application March 24, 1950, Serial No. 151,777

16 Claims. (Cl. 61—23)

1

This invention relates to apparatus for swimming pools, tanks and like receptacles, and more particularly to equipment for removing surface liquid in and on which scum, dust, leaves and other debris tends to gather to the detriment both of the appearance of the pool and of enjoyment of the users.

A principal object of the invention is to provide novel surface skimming equipment which has improved means for regulation of the swimming rate.

Another object is to devise equipment of the described type consisting of a minimum number of parts which are of simple design and inexpensive to manufacture.

Another object is to provide apparatus which is easy to install and self-adjusting in operation.

Still another object is to provide for easy adjustment and control of the quantity and rate of removal of surface liquid.

Still other objects and advantages will be apparent from the detailed description which follows.

A present preferred embodiment of the present invention consists essentially of two parts, a float member and a fixed support which is connected to an outlet. The two parts have a telescoping relation with each other and together form an open chamber in which a quantity of the liquid in the pool or tank is segregated and separated from the main body of the liquid. This chamber will vary in size with changes in the depth of liquid in the pool which cause upward or downward movement of the float member. By withdrawing liquid continuously from the chamber a differential in liquid levels of pool and chamber is created which affects the buoyancy of the float member with the result that this member is caused to float below the liquid level of the pool but above the liquid level in the chamber. As a result a top layer of liquid spills over the top of the float member and into the chamber whence it is withdrawn by gravity or by a pump through the outlet connection to the fixed support. The float member automatically adjusts itself to the difference in liquid levels created by the withdrawal of liquid from the chamber.

In order to illustrate the invention and the manner of its use concrete embodiments thereof are shown in the accompanying drawings in which:

Figure 1 is a diagrammatic view partly in vertical section and partly in elevation of a portion of a swimming pool with a skimming device installed;

2

Figure 2 is a vertical sectional view on an enlarged scale through one form of skimming device during operation, the section being taken on the line 2—2 of Figure 3 with the outlet pipe shown in elevation;

Figure 3 is a plan view on a reduced scale of the device shown in Figure 2; and

Figure 4 is a vertical sectional view similar to Figure 2 through a modification of the invention.

10 In Figure 1 is illustrated a typical installation of equipment of the present invention in a swimming pool, the surface water which is withdrawn being filtered and then returned to the pool. The skimming device indicated generally at A, and 15 of either of the types illustrated in detail in the other figures of the drawing, is mounted on outlet pipe B at the edge of pool C. Outlet pipe has a hand-operated control valve D in advance of a pump E of any suitable or desired type, the 20 discharge line F of the pump leading to a filter G of known or suitable type and thence by line H back into the pool. When the withdrawn liquid is not recirculated, the pump E and filter G may be omitted and withdrawal effected solely by 25 gravity flow.

Referring now to Figures 2 and 3 for a detailed showing of one form of the skimming device A, the latter comprises a chamber formed of but two parts 6 and 7 in telescoping relation 30 with each other. Part 6 is a fixed member in the form of a plate or disk attached horizontally to the upturned open end of outlet pipe B at a suitable distance below the level of the body of liquid in pool C. Mounted for vertical movement 35 and enclosing fixed member 6 is float member 7 open at both ends but provided at its upper end with an internal sealed annular air chamber 8 formed by inner wall 9, bottom wall 10 and top wall 11. Bottom wall 10 will engage the upper face of plate 6 to act as a stop whenever the body of liquid in pool C is at or below the top of outlet pipe B. In the form shown plate 6 is circular and float member 7 is cylindrical but it is to be understood that these parts can be made 40 in other shapes such as square, oval, triangular, etc. if desired. There is sufficient clearance between the outer edge of plate 6 and the skirt or lower portion of float member 7 which telescopes thereover to permit free upward and downward movement of float member 7 as the liquid level α in the pool changes. When liquid is not being withdrawn by outlet pipe B, float member 7 rides or floats in the pool with its annular flat top 11 well above the surface α , the two parts 6 and 7 45 cooperating to provide a chamber above plate 6

and enclosed by the portion of float member 7 above plate 6, this open chamber containing a body of liquid which is segregated from the main body in pool C.

The device functions as follows: On opening valve D in outlet line B liquid will be withdrawn from the open chamber above plate 6 either by gravity or by the operation of pump E. The level of the liquid in the chamber will fall. This will automatically effect a change in the position of float member 7 relative to plate 6 since there is less liquid in the open chamber and hence a lower liquid level there. Member 7 will preforce move downwardly seeking a point of equilibrium which will be determined by its mass and buoyancy as affected by the differential between the level of the main body of liquid in the pool and the lowered level in the open chamber above plate 6. Float member 7 will be depressed until it floats below the level *a* of the main body and surface liquid will pour over the top 11 and into the open chamber, member 7 finding a point of balance or equilibrium with the level of fluid in the open chamber at a position such as *b* (Figure 1) as compared with level *a* of the main body. It is usual practice to set the flow through outlet pipe B so that float member 7 adjusts itself with its top about $\frac{1}{8}$ of an inch below main liquid level *a*.

A low narrow upstanding annular flange or lip 12 may be provided at the outer edge of top 11 of float member 7. This has been found to have the further effect of enlarging (so to speak) the mouth or central opening in member 7 which admits the overflow liquid into the chamber above outlet pipe B, thereby increasing the "draw" of the device; in other words overflow begins at flange 12 instead of at the inner edge of top 11 as is the case when flange 12 is omitted. Flange or lip 12 may also be utilized to retain a flat screen (not shown) on the top of float member 7 to intercept and retain leaves and other debris which might clog pipe B or foul pump E.

Part 6 and 7 may be made of any suitable or desired material. Metals not subject to corrosion, such as copper and brass are suitable. The preferred materials, however, are plastic compounds such as certain of the well-known phenol-condensation products including Lucite, tenite, etc. Since there are no critical tolerances, part 7 as well as part 6 may be inexpensively molded of plastic such as Lucite which in addition to its inherent suitability also presents an attractive appearance. Float member 7 may be initially formed in two parts of equal size by a split mold operation and then integrally united to form the sealed float chamber 8.

Dimensions of the parts of the overflow or skimming device shown in Figures 2 and 3 for a typical installation are as follows: Plate or disc 6 is of Lucite plastic $\frac{3}{8}$ " inch and $7\frac{1}{8}$ " in diameter. It is formed with flutes or depressions 6a on its upper face, as shown, to reduce weight. A central opening is drilled and tapped to screw on to the upturned vertical end of outlet pipe B. Float member 7, also of Lucite plastic, has walls $\frac{1}{8}$ " in thickness throughout. The internal diameter of the lower end or skirt which telescopes over plate 6 is $7\frac{3}{4}$ ", providing $\frac{1}{8}$ " clearance with plate 6. The reduced opening or mouth defined by air chamber 8 at the upper end has a diameter of $4\frac{3}{4}$ ". The upstanding annular flange 12 is $\frac{1}{2}$ " in height. This size is adequate for most pools; for very large pools the dimen-

sions are increased or two devices of the specified size may be utilized advantageously.

Figure 4 shows a modification in which a substantially fluid tight seal is maintained between the plate and float members at certain depths of liquid in the pool but at lesser depths free access of fluid to outlet pipe B is permitted. In this form A', the fixed plate or disc member 16 is upwardly flared from a hub portion 16a which is threaded onto the upwardly directed end section of outlet pipe B, which section has a series of small openings 25 in its side wall beneath a cap 26 which closes the top of the pipe, openings 25 being located above hub portion 16a of plate or disc member 16 but below a horizontal projection of the upper end of the latter. The outer edge of member 16 is recessed or otherwise arranged to receive and hold a packing ring 16b which bears against the telescoping lower skirt portion of float member 17 to form a substantially fluid tight seal but the packing ring has a hard smooth outer surface which offers a minimum of frictional resistance to movement of float member 17. Toward its upper portion the skirt of float member 17 is outwardly expanded in a smooth curve 27 into an enlarged offset which disposes its wall 28 out of contact with plate 16 and provides clearance around packing 16a. Above section 28 float member 17 has an inwardly extending annular sealed air chamber 18 formed by inner cylindrical wall 19, bottom wall 20 and top wall 21. In this form flat top 21 extends radially beyond chamber 18 and the cylindrical wall of member 17. Top 21 may have a low, narrow upstanding flange or lip 22 around its edge.

The device of Figure 4 is made in a similar manner and operates similarly to the first form of the invention previously described except that when the main body of liquid falls to a predetermined level the descending movement of float member 17 brings the expanded outwardly curved wall 27 of the offset to and below packing 16b on fixed plate 16, the liquid removed by pipe B is no longer confined to that which spills over top 21 but will include liquid moving upwardly through the lower end portion of member 17 and around packing 16b and into the wide clearance space between the latter and wall 28 provided by the enlarged offset. Liquid will continue to pass in this manner through this lower passageway to outlet pipe B in unrestricted volume until level *a* of the main body has fallen to such an extent that bottom wall 20 of float chamber 18 comes to rest on the peripheral upper edge of fixed plate 16. As the pool is refilled to restore it to its original level, float member 17 will rise and sloping wall 27 will guide its lower skirt portion into telescoping relation again with plate 16. Cap 26 on the upper section of outlet pipe B and small outlet opening 25 will screen out leaves and large pieces of debris but a fine mesh screen (not shown) seated on top 21 or surrounding the upper end of skimming device A' is still desirable in most instances.

From the above it will be apparent that the equipment of the present invention for skimming and like operations is extremely simple both in construction and in operation and that it is easily controlled by the setting of outlet valve D. If a variable speed pump is provided at E in the outlet line, valve D may be dispensed with and control then effected by modifying the speed of the pump. The provision of an open chamber for liquid, separate from the main body of liquid,

makes the float member 7 or 17 self-adjusting when liquid is withdrawn by outlet line B and provides for continuous removal of liquid at the very surface of the body and in any desired volume. In normal operation the float member 7 or 17 is not more than one-eighth inch below the level of the body of liquid which is being skimmed. It will be seen that the sensitivity of the system depends upon the rate at which the skimmed liquid is drawn off by the circulation pump, or by the drain pipe in the case of a gravity type outflow. This is in contrast to previously known skimming devices supported by a float which floats entirely in the pool liquid, and the position of whose overflow lip is highly sensitive to the buoyancy of the float. Adjustment of such devices to skim at the desired rate is very difficult, while by contrast, the skimming rate of the present device depends upon the liquid lever 20 maintained inside the device, and hence directly upon the easily controlled rate of outflow through pipe B.

The invention has been illustrated in its application to swimming pools but is directly useful generally wherever surface layers are to be removed from bodies of liquid for any purpose and especially when this is to be done with a minimum of disturbance of lower layers of liquid. By utilizing a packing or seal between the fixed plate 16 and the floating member 11, seepage between these parts such as occurs between members 6 and 7 of Figures 2 and 3, is avoided, as for the skimming device of Figures 4 and 5, so long as the body of liquid is maintained at a sufficiently high level to keep enlarged offset or flared wall 27 above plate 16 (as in Figure 4) only liquid from the surface can be withdrawn through outlet pipe B.

While the invention has been herein disclosed in what are now believed to be preferred forms, it is to be understood that the invention is not limited to the specific details thereof but covers all changes, modifications and adaptations within the scope of the appended claims.

I claim:

1. In equipment for skimming swimming pools, tanks and the like containing a body of liquid, the combination of: side and bottom walls forming a chamber positioned in said body of liquid near the surface thereof and constructed and arranged to hold a quantity of liquid segregated from the main body of liquid, said chamber walls including a vertically movable side wall member which has a substantially liquid tight working fit with adjoining stationary wall portions of the chamber, said member having a liquid overflow lip positioned near the surface of the main body of liquid and over which surface liquid from said main body may spill into said chamber, float means operatively connected to said movable wall and arranged to float in the liquid contained inside said chamber, whereby said over-flow lip will rise and fall with the liquid level inside said chamber, and an outflow conduit for removing liquid from said chamber.

2. In equipment for skimming swimming pools, tanks and the like containing a body of liquid, the combination of: side and bottom walls forming a chamber positioned in said body of liquid near the surface thereof and constructed and arranged to hold a quantity of liquid segregated from the main body of liquid, said chamber walls including a vertically movable side wall member which has a substantially liquid tight working fit with adjoining stationary wall portions of the

chamber, said member having a liquid overflow lip positioned near the surface of the main body of liquid and over which surface liquid from said main body may spill into said chamber, float means operatively connected to said movable wall and arranged to float in the liquid contained inside said chamber, whereby said over-flow lip will rise and fall with the liquid level inside said chamber, an outflow conduit for removing liquid from said chamber, and a circulation pump connected to said outflow conduit.

3. A skimming device for pools, tanks and the like comprising a fixedly supported circular plate, a cylindrical member telescoped over said plate with a slidably fit, means on said member providing an air chamber above said plate and serving as a stop to engage the latter to limit the downward movement of said member, the top wall of said chamber forming an annular flat top for said member over which liquid will flow into the open chamber above said plate formed by said cylindrical member when the liquid level in said open chamber is lowered by withdrawing fluid from said open chamber, and an outflow conduit for removing liquid from said chamber.

4. A skimming device for pools, tanks and the like comprising a fixedly supported circular plate, a cylindrical member telescoped over said plate with a slidably fit, said member having means at its upper end forming an air chamber which reduces the opening at that end and which has a flat annular top, a low flange extending above said top around the edge thereof, and an outflow conduit for removing liquid from said chamber.

5. A skimming device for pools, tanks and the like comprising a fixedly supported horizontally disposed plate, a float member open at both ends having a skirt portion in telescoping relation with said plate and a sealed air chamber above said plate, said float member and said plate cooperating to provide an open chamber for segregating a quantity of liquid in the pool from the main body of liquid, said air chamber being located within said open chamber so as to float in the liquid contained therewithin, said float member having a flat top which projects beyond the side walls thereof over which liquid from the main body will flow into said open chamber when said member is depressed by withdrawal of liquid from said open chamber, and an outflow conduit for removing liquid from said chamber.

6. A skimming device for pools, tanks and the like comprising a fixedly supported horizontally disposed circular plate, a cylindrical float member open at both ends having its lower portion telescoped over said plate for vertical movement relative thereto and having a sealed air chamber above said plate, said float member and said plate forming a chamber open at the top to hold a quantity of the liquid in the pool separate from the main body of liquid, said air chamber being located within said open chamber so as to float in the liquid contained therewithin, said float member having a flat annular top which extends beyond the vertical walls thereof, over which top liquid from the main body will flow into the said open chamber when said member moves downwardly beneath the level of the main body of liquid in response to withdrawal of liquid from said open chamber, said flat top having a low up-standing flange around the outer edge thereof, and an outflow conduit for removing liquid from said chamber.

7. A skimming device for pools, tanks and the like comprising a fixedly supported circular plate,

a cylindrical float member having a skirt telescoped over said plate with a close sliding fit to form with said plate a chamber open at the top for segregating a quantity of liquid from the main body of liquid in the pool, float means within the confines of said member above said plate, said member having an annular flat top over which liquid from the main body flows into said chamber where said member moves downwardly beneath the level of the main body of liquid in response to withdrawal of liquid from said open chamber, said member having an enlarging offset intermediate its ends to permit liquid to by-pass said plate and enter said chamber from beneath when the main body of liquid falls to a predetermined level, and an outflow conduit for removing liquid from said chamber.

8. A skimming device for pools, tanks and the like comprising in combination a circular plate having a packing ring on its outer edge, and a cylindrical member open at both ends having a skirt portion to telescope over said plate and to slidably engage said packing ring to make a fluid tight seal, a float inside and connected to said cylindrical member, said member having an enlarged offset portion to permit liquid to by-pass said plate in certain positions of said member relative to said plate, and an outflow conduit for removing liquid from said chamber.

9. A skimming device for pools, tanks and the like comprising in combination a circular plate having a packing ring on its outer edge, and a cylindrical member open at both ends having a skirt portion to telescope over said plate and to slidably engage said packing ring to make a fluid tight seal, a float inside and connected to said cylindrical member, said member having an enlarged offset portion to permit liquid to by-pass said plate in certain positions of said member relative to said plate, said offset portion of said member joining said skirt portion thereof in a smooth curve to permit free movement of said member into and out of fluid tight sealing engagement with said plate, and an outflow conduit for removing liquid from said chamber.

10. In skimming equipment for swimming pools, tanks and the like the combination with a vertical outlet pipe of an upwardly dished plate mounted on said pipe, said plate having a packing ring on its outer edge, an open-ended float member having a skirt portion telescoped over said plate to engage said packing ring and form a fluid tight seal, float means on the upper portion of said member to engage said plate as a stop to limit the downward movement of said member on said plate, means on said member providing a by-pass for fluid around said plate as said member approaches the lower limit of its movement.

11. In skimming equipment for swimming pools, tanks and the like the combination with a vertical outlet pipe of an upwardly dished plate mounted on said pipe, said plate having a packing ring on its outer edge, an open-ended float member having a skirt portion telescoped over said plate to engage said packing ring and form a fluid tight seal, float means on the upper portion of said member to engage said plate as a stop to limit the downward movement of said member on said plate, means on said member providing a by-pass for fluid around said plate as said member approaches the lower limit of its movement, said pipe having a closed end and ports in its side wall above said plate but below a horizontal projection of its upper end.

12. In equipment for skimming swimming pools, tanks and the like the combination of a circular plate mounted horizontally beneath the surface of a body of liquid, and a cylindrical float member supported by the liquid in telescoping relation with said plate, said member having an air chamber partially closing the upper end thereof, said float member and said plate forming a chamber in which a quantity of liquid is separated from the main body of liquid, and means for withdrawing liquid from said chamber automatically to depress said float member relative to said plate and to cause liquid from the main body to overflow said member into said chamber.

13. In equipment for skimming swimming pools, tanks and the like containing a body of liquid, the combination of: a chamber positioned in said body of liquid near the surface thereof and constructed and arranged to hold a quantity of liquid segregated from the main body of liquid, said chamber being partly defined by fixedly mounted wall means and partly defined by a vertically movable side wall structure having an overflow portion over which liquid from the main body can spill into said chamber when said overflow portion is lowered below the level of said main body, and float means operatively connected to said movable side wall structure and arranged to float in the liquid inside said chamber, whereby said overflow portion of said side wall structure will rise and fall with the liquid level inside said chamber, and an outlet for removing liquid from said chamber.

14. A skimming device for pools, tanks and the like comprising a fixedly supported horizontally disposed plate, a float member open at both ends having a skirt portion in telescoping relation with said plate and a sealed air chamber above said plate, said float member and said plate cooperating to provide an open chamber for segregating a quantity of liquid in the pool from the main body of liquid, said air chamber being located within said open chamber so as to float in the liquid contained therewithin, said float member having an overflow edge over which liquid from the main body will flow into said open chamber when said member is depressed by withdrawal of liquid from said open chamber, and an outflow conduit for removing liquid from said chamber.

15. In equipment for skimming swimming pools, tanks and the like containing a body of liquid, the combination of: an open chamber comprising a fixedly supported bottom wall structure, a side wall structure surrounding said bottom wall structure and movable vertically relative to said bottom wall structure in sliding engagement with the periphery thereof, said chamber having an overflow portion over which liquid from the main body can spill into said chamber when said overflow portion is lowered below the level of said main body by withdrawal of liquid from said chamber, a float included in the chamber located inside the chamber and operatively connected to said side wall structure, so as to float in the liquid contained inside the chamber, whereby said overflow portion of the chamber rises and falls with the liquid level inside the chamber, and an outlet for removing liquid from said chamber.

16. In equipment for skimming swimming pools, tanks and the like containing a body of liquid, the combination of: an open chamber comprising a fixedly supported bottom wall

structure, a side wall structure surrounding said bottom wall structure and movable vertically relative to said bottom wall structure in sliding engagement with the periphery thereof, an overflow lip on said side wall structure over which liquid from the main body can spill into the chamber when said overflow lip is lowered below the level of said main body by withdrawal of liquid from said chamber, a float fixedly connected to the side wall structure and arranged inside said chamber near the upper end thereof, so as to float in the liquid contained inside the chamber, whereby the said overflow lip rises and falls

with the liquid level inside the chamber, and an outlet for removing liquid from said chamber.
